UNITED STATES PATENT OFFICE.

FRANK KOGUT, OF PASSAIC, NEW JERSEY.

NUT-CRACKING DEVICE.

1,052,926.

Specification of Letters Patent. Patented Feb. 11, 1913.

Application filed September 16, 1911. Serial No. 649,662.

To all whom it may concern:

Be it known that I, FRANK KOGUT, a subject of the Emperor of Austria-Hungary, residing at Passaic, in the county of Passaic, and State of New Jersey, have invented 5 certain new and useful Improvements in Nut-Cracking Devices, of which the following is a specification, reference being had therein to the accompanying drawing.

10 This invention relates to nut cracking devices, and the primary object of my invention is to provide a nut cracking device consisting of comparatively few parts that can be easily assembled.

15 Another object of this invention is to provide a nut cracking device constructed upon the principle of a punch for crushing and cracking the shell of a nut.

20 A further object of this invention is to provide a nut cracking device than can be safely used and manufactured at a comparatively small cost.

25 With the above and other objects in view, the invention resides in the novel construction, combination and arrangement of parts to be hereinafter specifically described and then claimed.

30 Reference will now be had to the drawing, wherein like numerals of reference designate corresponding parts throughout the several views, in which:—

35 Figure 1 is a front elevation of the nut cracking device partly broken away and partly in section, Fig. 2 is a horizontal sectional view of the nut cracking device taken on the line II—II of Fig. 1, Fig. 3 is a front elevation of the device showing the plunger or punch rod in a lowered position, and Fig. 4 is a bottom plan view of the 40 plunger or punch rod.

The reference numeral 1 denotes an oblong base plate having the top thereof provided with a central recess or pocket 2 adapted to receive the nut to be cracked.

45 The sides or ends of the base plate 1 are provided with sockets 3 for the lower ends of oppositely disposed vertical uprights 4. The lower ends of the uprights 4 are secured in the sockets 3 by screws 5 or other 50 fastening means extending through said uprights into the base plate 1. The upper

ends of the uprights 4 extend into sockets 6 provided therefor in the under side of a cross head 7, and the upper ends of said uprights are secured within the sockets 6 55 by detachable screws 8 or other fastening means.

The cross head 7, intermediate the ends thereof, has a vertical opening 10 for a plunger or punch rod 11. The upper end of 60 the plunger has a punch head or button 12 and encircling said plunger, between the head 7 and the head 12, is a coiled spring 13.

The lower end of the plunger 11 has a transverse slot 14 for a guide bar 15 that 65 is retained in engagement with the plunger by a screw 16 or other fastening means. The ends of the transverse guide bar 15 extend into vertical grooves 17 provided therefor in the confronting faces of the uprights 4. 70 The exterior lower end of the plunger or punch rod 11 has an integral inverted cup-shaped cracking head 18, said head having a central socket 19 for the shank 20 of a cracking tool or chisel 21. The shank 20 is 75 frictionally held within the socket 19 and the cracking tool is adapted to crack the shell of a nut while the head 18 inclosing the nut, besides assisting in crushing the shell, prevents particles of the shell from 80 being thrown from the base plate 1.

The plunger of punch rod 11 is provided with a notch 22 intermediate the ends thereof and adapted to engage in this notch is a hook 23 pivotally connected to the under 85 side of the cross head 7, said hook retaining the plunger or punch rod in a lowered position, with the spring 13 under tension. When the plunger or punch rod is in this position, the device can be easily packed 90 or stored away without occupying a large space.

The device in its entirety is made of light and durable metal and is susceptible to ornamentation, whereby it will present a 95 neat appearance upon a dining table.

What I claim is:—

In a device of the character described, a stationary and a shiftable recess member, one coöperating with the other, the recesses 100 of said members opposing each other, one of said members adapted to support a nut,

means for shifting the other of said members toward the nut supporting member to extend over the nut, and a splitting device detachably secured centrally of said shift-
5 able member and provided with an edge lying within the recess of said member and capable of contacting with the nut to split it when the shiftable member has been

moved to extend around the nut supported by the other of said members.

In testimony whereof I affix my signature in the presence of two witnesses.

FRANK KOGUT.

Witnesses:

CHARLES SLAFF,
GIRER DUBY.
